UNITED STATES PATENT OFFICE.

ARNOLD FLESH, OF NEW YORK, N. Y.

DESIGN FOR A BUTTON.

SPECIFICATION forming part of Design No. 13,256, dated August 22, 1882.

Application filed July 22, 1882. Term of patent 3½ years.

To all whom it may concern:

Be it known that I, ARNOLD FLESH, of the city, county, and State of New York, have invented a new and Improved Design for Buttons, of which the following is a full, clear, and exact description.

The drawing is a plan view of a button illustrating my new design.

The leading feature of my design consists of a representation of Henry W. Longfellow in relief and surrounded by the words "Henry W. Longfellow" in the arc of a circle. Directly beneath the figure is the date 1882.

The surface or background can be stippled or made plain, as may be desired.

Having thus described my invention, I claim as new and desire to secure by Letters Patent— The design for a button herein shown and described, the same consisting of the button having a representation of Henry W. Longfellow in relief, surrounded by the words "Henry W. Longfellow" in the arc of a circle, and having the date 1882 beneath it, as set forth.

A. FLESH.
